UNITED STATES PATENT OFFICE.

THOMAS A. O'NEILL, OF NEW YORK, N. Y.

AUTOMATIC GAS CUT-OFF.

Application filed February 25, 1924. Serial No. 695,064.

To all whom it may concern:

Be it known that I, THOMAS A. O'NEILL, a citizen of the United States, residing at New York city, in the county of New York 5 and State of New York, have invented new and useful Improvements in Automatic Gas Cut-Offs, of which the following is a specification.

This invention relates to automatic gas cut-offs for use in connection with steam or hot water boilers.

The principal object of the invention is the provision of an automatic gas cut-off wherein the valve for controlling the flow of 15 gas to the burner is held opened by a mechanism operable by reason of the water level in the boiler, whereby the water upon reaching its low level will automatically close the valve to shut-off the flow of gas to the 20 burner, thus assuring an absolutely safe appliance for gas heated boilers.

Another object of the invention is to provide a device of the type mentioned which may be easily applied to gas heated boilers 25 now in use, without affecting the present construction of the same.

With these and other objects in view, the invention resides in certain novel construction and combination and arrangement of 30 parts, the essential features of which are hereinafter fully described, are particularly pointed out in the appended claims, and are illustrated in the accompanying drawing, in which:—

35 Figure 1 is a side elevation of my invention shown applied to a boiler.

Figure 2 is an enlarged detail sectional view of a portion of the same and showing the valve in open position.

40 Figure 3 is a view similar to Figure 2 but showing the valve in closed position.

Figure 4 is a detail vertical sectional view showing a slight modification.

45 Figure 5 is a view similar to Figure 4 but showing a still further modification.

Referring more particularly to the drawing, the reference numeral 10 designates the steam boiler of the usual well-known construction and beneath which is mounted 50 a gas burner 11. The boiler is normally filled with water to a point adjacent the top thereof and which water is adapted to be heated to a steaming point by the burner 11, and the steam utilized for heating or like purposes.

55 In the present style of boilers, it often

happens that the burner continues to heat the boiler after the water has reached its low level and which is the cause for much dissatisfaction. It is therefore the purpose 60 of my invention to overcome this objection by providing a means which is automatically operable for shutting-off the flow of gas to the burner when the water has reached its low level.

The numeral 12 designates a gas supply pipe leading to the burner 11, and in which is mounted a valve 13. The valve 13 comprises a casing 14 of separable sections, within which is mounted the plunger rod 15 70 having a manipulating knob 16 at its outer end and a valve head 17 intermediate the ends for closing a passageway 18 communicating with the fuel supply pipe 12 and the burner 11. An expandible spring 19 75 encircles the inner end of the plunger rod and is interposed between the head 17 and the end of the casing so as to normally hold the valve head in closed position over the passage way 18. A locking pin 20 is mounted 80 for sliding movement in the casing 14 at right angle to the longitudinal axis of the plunger rod 15. The pin 20 is formed with a head 21 for the abutment of one end of a spring 22, the other end of the spring resting against the valve casing 14. The free end of the pin is adapted to co-act with a depression or recess 23 in the valve head as shown in Figure 2 of the drawing.

85 Supported by the boiler 10 and at one side thereof is a tank 24 which is arranged adjacent the bottom of the boiler. Pipes 25 and 26 connect the tank 24 with the boiler 10 and serve to support the same in spaced relation thereto. It will be seen that as the 90 boiler is filled with water, the same will flow into the tank through the pipes and therein seek its own level. Secured to the bottom of the tank 24 is a rod 27 which rests on the head 21 of the pin 20 for a purpose to be 100 described.

In operation, the plunger 13 is moved inwardly to uncover the passage way 18 and to bring the recess 23 into register with the pin 20. The weight of the water 105 in the tank 24 causes a slight downward movement of the tank which in turn causes the pin to be seated in the recess 23. The flow of gas from the supply pipe 12 is free to pass to the burner 11 and the burner 110 is lighted for heating the boiler. As steam is generated, the supply of water in the

tank and boiler decreases until the level reaches the position shown in Figure 3 of the drawing at which time the spring 22 overcomes the weight of the tank and releases the pin 20 from engagement with the recess 23, permitting the spring 19 to move the valve head 17 over the passage-way 18 thereby shutting off the flow of gas to the burner and preventing overheating of the boiler. In the form shown in Figures 1 to 3 inclusive, the tank is connected to the boiler by straight pipes which will permit a slight movement of the tank necessary to bring the pin into coaction with the recess 23. This movement is only a fraction of an inch and if desired, pipes 30 and 31 as shown in Figure 4 of the drawing might be connected to the tank and boiler by means of flexible connections 32 in the form of a ball and socket joint. This will permit free movement of the tank with respect to the boiler without placing a strain upon the connecting pipes.

In Figure 5 there is shown a further modified form of connection between the tank and the boiler wherein use is made of coils of pipe 33 and 34. This will permit ample movement of the tank with respect to the boiler as will be clearly understood.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:

1. In a device of the class described, the combination with a boiler, a burner for heating said boiler, a valve, manually operable means for opening said valve to permit fuel to flow to said burner, means for holding said valve in open position when the level of water in the boiler is above a predetermined height including a movable tank in open communication with said boiler, and means operable for closing said valve when the level of water reaches a low level.

2. In a device of the class described, the combination with a water boiler, a burner for heating the water in said boiler, a valve for controlling the flow of fuel to said burner, manipulating means for opening said valve, a tank, means for supporting said tank from said boiler for vertical movement with respect thereto and for permitting communication between the boiler and tank, and means operable by the weight of said tank and its contents for holding said valve in open position.

3. In a device of the class described, the combination with a water boiler, a burner

for heating the water in said boiler, a valve for controlling the flow of fuel to said burner, manipulating means for opening said valve, a tank, means for supporting said tank from said boiler for vertical movement with respect thereto and for permitting communication between the boiler and tank, and means operable by the weight of said tank and its contents for holding said valve in open position, and means automatically operable when the contents of said tank is reduced to a low level to cause the valve to move to shut-off position.

4. In combination with a water boiler, a burner for heating the water in said boiler, a valve for controlling the flow of gas to said burner comprising a sliding valve, means for normally holding said valve in closed position, manipulating means for moving said valve to open position, a recess formed in said valve, a pin for co-action with said recess when the valve is in open position, means for holding said pin seated in said recess when the water in said boiler is above a predetermined level, and means for returning said valve to normal position upon the releasing of said pin.

5. In combination with a water boiler, a burner for heating the water in said boiler, a valve for controlling the flow of gas to said burner comprising a sliding valve, means for normally holding said valve in closed position, manipulating means for moving said valve to open position, a recess formed in said valve, a pin for co-action with said recess when the valve is in open position, and means for holding said pin seated in said recess when the water in said boiler is above a predetermined level, means for releasing said pin from said recess when the level of water reaches a low level, and means for returning said valve to normal position upon the releasing of said pin.

6. In combination with a water boiler, a burner for heating the water in said boiler, a valve for controlling the flow of gas to said burner comprising a sliding valve, means for normally holding said valve in closed position, manipulating means for moving said valve to open position, a recess formed in said valve, a pin for co-action with said recess when the valve is in open position, means for holding said pin seated in said recess when the water in said boiler is above a predetermined level, means for automatically lifting said pin from said recess when the level of water reaches a low level, and means for simultaneously moving said valve to closed position upon the operation of said last mentioned means.

7. In combination with a water boiler, a burner for heating the water in said boiler, a valve for controlling the flow of gas to said burner comprising a sliding valve,

means for normally holding said valve in closed position, manipulating means for moving said valve to open position, a recess formed in said valve, a pin for co-action with said recess when the valve is in open position, a tank mounted above said valve, flexible pipes connecting said tank with said boiler for permitting the water in said boiler to seek its level in said tank and for permitting a slight vertical movement of said tank with respect to said boiler, a rod secured to said tank and co-operative with said

pin to move the pin into co-acting engagement with said recess when the water in said tank is above a predetermined level, and 16 means for lifting said tank when the water therein reaches a low level and for releasing said pin from said recess, and means for automatically moving said valve to closed position upon the operation of said last 20 mentioned means.

In testimony whereof I have affixed my signature.

THOMAS A. O'NEILL.
